UNITED STATES PATENT OFFICE.

HENRY L. ST. JAMES, OF MARSHALL, TEXAS.

PISTON-PACKING.

SPECIFICATION forming part of Letters Patent No. 377,442, dated February 7, 1888.

Application filed October 28, 1887. Serial No. 253,602. (No model.)

To all whom it may concern:

Be it known that I, HENRY L. ST. JAMES, of Marshall, in the county of Harrison and State of Texas, have invented a new and useful Improvement in Steam Piston-Packing; and I do hereby declare that the following is a full and exact description of the same, reference being had to the accompanying drawings, and to the letters of reference marked thereon.

10 This invention relates to certain novel improvements in steam piston-packing, which improvements will be fully understood from the following description and claims, when taken in connection with the annexed drawings, in which—

15 Figure 1 is a side view of the improved piston and its packing. Fig. 2 is a diametrical section through Fig. 1, taken in the plane indicated by dotted line $x-x$ on Fig. 3. Fig. 3 is a section through Fig. 1, taken in the plane indicated by dotted line $y-y$ thereon. Fig. 4 is a sectional view of one of the piston-packing segments, showing the packing-rings on the stem thereof. Fig. 5 is a detail of one of the 20 cut rings. Fig. 6 is a sectional detail of the piston-stem.

25 Referring to the annexed drawings, A designates a piston-head, and B designates the piston-rod thereof. The piston-head, the peculiarities of which I shall hereinafter describe, is bored out straight, and the rod B is constructed with a cylindrical entering portion, B', having a shoulder at a and an annular flange at b . When this rod is driven into the 30 piston, the latter is shrunk on it, after which the flange a is riveted into a countersink in the face of the piston, thereby positively connecting the piston to its rod without the use of nuts, and leaving the face of the piston and 35 the end of its rod flush. The piston-head is cast entire, and it has two annular grooves in 40 its circumference, which grooves are lettered c e , and they are separated by an annular septum, d . For the purpose of description, 45 the piston-head is divided into two parts in planes at right angles to the longitudinal axis of the rod B, one of which planes is represented in the sectional view, Fig. 3. The parts on the opposite side of the septum d are ex- 50 acly like those which I am about to particu-

larly specify.

C designates an interior hub, which is between the face and back plates, $e-e$. From this

hub radiate six or any other suitable number of arms or brackets, f , which re-enforce 55 the piston, and which are radially with respect to the axis of the piston-head. A bored out to points suitably near the hub, from which points the front and back plates have steam-ports passing through them and lettered $g-g$. 60

D designates T-shaped segmental pistons, the cylindrical rods h of which enter the bores in the radial arms or brackets f , and are each provided near their inner ends with annular grooves i , in which are applied spring packing-rings j , the cuts of which break joints. The ends of the segmental portions of said segments do not touch each other, and, collectively, these segments make up an expansible bearing for a split ring, G , which incloses 70 them and affords the expansible elastic packing proper and the wearing-surface of the piston. The ends of the cylindrical rods h have central apertures, n , extending into them, a short distance from which radiate apertures 75 n' , that admit steam into the grooves i to expand the rings j and pack them steam-tight against the bores in the radial arms f .

It will be observed that the piston-head is cored from the slots k to the hub on both sides 80 of the septum d , thereby leaving an unbroken flat surface to the steam at both ends of the piston. By thus coring out I render unnecessary the subsequent plugging of the end plates of the piston-head.

Having described my invention, I claim—

1. The within-described piston head cast entire and having radial arms bored out, in combination with the piston-segments, the steam-ports in the piston-plates, and stems of said segments, packing expansible rings on said stems, and the expansible packing-rings enclosing the said piston-segments, substantially as described.

2. A piston-head cast entire and cored out 95 from its slots to its hub, in combination with the radial arms, the steam-ports g , and the T-shaped pistons having rods perforated at $n-n'$, and provided with suitable packing-rings, substantially as described.

In testimony whereof I affix my signature in presence of two witnesses.

HENRY L. ST. JAMES.
